My Kingdom for Some Structure, Napkin #2—All Things Considered image, <http://transom.org/2013/my-kingdom-for-some-structure/>, by Rob Rosenthal, posted Mar. 27, 2013.*

Primary Examiner — Kevin K Rudzinski

(57) **CLAIM**

The ornamental design for a display panel for a graphical user interface with flip notification, as shown and described.

DESCRIPTION

FIG. 1 is a front view of an exemplary embodiment of our new design;

FIG. 2 is a front view of another exemplary embodiment thereof; and,

FIG. 3 is a front view of another exemplary embodiment thereof.

The broken lines in the drawings illustrate the display screen and portions of the graphical user interface and form no part of the claimed design.

1 Claim, 3 Drawing Sheets
